ELECTRIC STERILIZER FOR HYPODERMIC
SYRINGES AND THE LIKE

Raymond V. Brandt, Clermont, Iowa

Application March 9, 1938, Serial No. 194,952

5 Claims.

(Cl. 21—86)

This invention relates to electric sterilizers and more particularly to a device for sterilizing hypodermic syringes, surgical and dental tools, and the like.

5 The invention has for its principal object to produce a simple yet practical and efficient electrically heated sterilizer device which is effectively insulated and constructed and arranged so that the sterilizing liquid is quickly heated and maintained in heated condition by direct contact with the electrodes, and whereby, also, the electric circuit becomes broken when the liquid is depleted or falls below a given level in the device.

With the foregoing and other objects to be attained the invention consists in the novel structure and parts, and, arrangements thereof as will hereinafter more fully appear in the following description and set forth with particularity in the appended claims, reference being had to the accompanying drawing forming a part of the specification and illustrating practical adaptations of the invention, in which

Figure 1 is a vertical section of one form of the sterilizer constructed in accordance with the invention;

Figure 2 is an inverted plan view of the base portion of the device;

Figure 3 is a fragmentary vertical section showing a modification of the liquid container and insulated casing, and

Figure 4 is a fragmentary view of a further modification of the device.

Referring now to the drawing, and more particularly to the structure shown in Figures 1 and 2 thereof, the numeral 10 designates the base portion of a casing which is generally cylindrical and has a central tubular column 11 extending upwardly therefrom. This casing base and tubular column may be constructed in any approved manner and of any suitable material. However, for practical purposes, it is preferably made of "Bakelite" or similar characteristic material and formed or molded integrally in one piece. As shown, the base 10 is open at its bottom and the tubular column 11 is also open-ended.

Supported within the casing is a metallic liquid container, the upper portion 12 of which is tubular and extends through the tubular column portion 11 of the casing, said portion 12 of the container having an out-turned annular flange 13 at its upper end which overhangs the adjacent end portion of the column 11 whereby to support the container within the outer casing.

At the lower end of the tubular portion 12 of the liquid container is a flared enlargement 14

having a depending annular collar or cylindrical flange portion 15 constituting the heating chamber 16 of the container. The cylindrical enlargement 15 is closed at its lower end by a head-plate 17 having an annular marginal flange 18 which is sleeved over the adjacent circumferential portion of the enlargement 15 and attached thereto, as by a screw-threaded engagement 19, as shown, or by any other approved method whereby to make the connection leak-tight. To afford a more dependable sealing effect, a gasket 20 may be provided between the head-plate 17 and the adjacent end of the cylindrical portion 15 of the container, which latter is provided with an inturned annular flange 21 for the purpose.

Mounted centrally on the inner face of the head-plate 17 and in direct electrical contact therewith is an electrode 22 of circular disc-like form and composed of carbon or any other material suitable for the purpose. Supported in spaced cooperative relation above the electrode 22 is a similar electrode 23, said electrodes being normally insulated from each other. Preferably, as shown, the upper electrode 23 is supported on a stem 24 composed of a suitable insulation material, said stem 24 having a reduced lower end portion 25 which extends through an axial opening in the lower electrode 22 and a registered opening in the head-plate 17, said reduced portion 25 terminating with a flanged enlargement 26 abutting the outer face of the plate 17 surrounding the central opening therein and the parts being engaged with leak-tight effect therebetween.

The upper electrode 23 is provided with a central opening through which a bolt 27 is inserted and extended through a longitudinal bore in the insulating stem 24, said bolt serving the dual purpose of holding the upper electrode in place on said stem 24 and as an electrical conductor 40 between said electrode and a circuit wire 28 which is attached at its end to the bolt 27 between a collar 29 abutting the flanged lower portion 26 of the insulating stem 24 and a clamping nut 30 provided on the screw-threaded lower portion of said bolt 27.

As above stated, the lower electrode 22 is in direct electrical contact with the head-plate 17 and, therefore, the electrical circuit connection for said lower electrode 22 is effected in a practical manner by attaching the end of the opposite circuit wire 31 to said plate 17, the connection being effected by providing the head-plate 17 with a terminal screw element 32 having a washer 55

33 and opposed nut 34 between which the end of said wire 31 is clamped.

In the use of the device the sterilizing liquid is provided in the inner metallic container up to a desired level within the tubular upper extension 12 thereof and the liquid in the lower enlargement or heating chamber 16 of the container completes the circuit between the two electrodes 22 and 23, whereupon the liquid becomes heated and circulates throughout its entire body within the container. In this connection, it is noted that should the liquid level fall below the upper electrode 23 the electrical circuit is thereby automatically broken and the liability of damaging the device is minimized by practically preventing the overheating and burning out of the electrodes.

In order to support hypodermic syringes and other implements for sterilization in the upper tubular portion of the device a detachable cap member or collar 35 is provided, said cap member, as shown, having an annular marginal flange 36 to fit over the adjacent end portion of the column 11 of the outer casing and a central opening 37 through which the instrument is inserted into the sterilizer. Preferably, interchangeable cap members 36 are provided, said cap members having central openings 37 of different diameters, and by which provision hypodermic syringes and other implements of various diameters may be suspended axially within the upper column portion 12 of the container and in spaced relation to the cylindrical wall thereof. In this connection, it may be also noted that said cap members 35 are preferably made of "Bakelite" or some other suitable material of non-electric conductivity and detachably secured in place by any suitable means, preferably by a screw-threaded attachment to the outer tube 11 as shown.

The structure may be modified as shown in Figure 3, wherein the outer casing, including the base and upper column portion, may be made of metal, as at 38, and the interior liquid container column portion 12 and widened base portion 14' thereof being spaced throughout from said outer casing, with an interposed insulating filler 39. As shown, the elongated upper portion of the filler 39 is cylindrical and corresponds to the form of the tubular column portions of the outer casing and inner liquid container, said insulating filler 39 having an annularly flanged lower portion 40 which is disposed between the top of the base portion of the outer casing and the annular enlargement 14' of the lower chambered portion of said liquid container. In other respects the structural arrangements may be as shown in Figure 1 of the drawing, except that the upper end flange 13 of the tube 12 is omitted and the cap member 35' is merely placed loosely on the tubular column.

60. A further structural modification is shown in Figure 4, wherein the inner container tube 12 is of the same diameter throughout the entire length thereof, that is to say, it has no enlarged heating chamber at its lower end, such as shown in Figures 1 and 3, and the bottom plate or closure member 17' has its annular flange portion 18' attached directly to the end of the tube 12. In lieu of the two electrode discs 22 and 23 as provided in the form of the device shown in Figure 1, a hollow cylindrical electrode 22', which may be of the same material as the hereinbefore described disc 22, is fitted in direct contact with the inner surface of the lower end portion of the tube 12 and also in end contact with the closure plate 17', which latter has the circuit wire 31

attached thereto substantially the same as in the modification shown in Figure 1. Disposed axially within the cylindrical electrode 22' and out of direct electrical contact therewith is a stud-like electrode 23' having an axial bore through which a securing bolt 27' extends, said bolt continuing through an axial opening in an insulating element 24' mounted in a central opening in the closure plate 17' and supporting said electrode 23' out of direct electrical contact with said closure plate 17', the bolt 27' being secured in substantially the same manner as the bolt 27 of the first herein described modification and said fastening means affording an attachment for the opposite circuit wire 28. In other respects the structure 15 may be the same as in either of the two hereinbefore described modifications.

The hypodermic syringe or other article to be sterilized is shown conventionally in the drawing by dotted lines in Figure 1 thereof and designated generally by the numeral 41.

Obviously, the structure may be modified in many respects other than herein specifically mentioned, within the spirit and scope of the invention as defined in the appended claims. 25 The invention, therefore, is not limited to the specific constructions and arrangements shown in the accompanying drawing.

What is claimed is:

1. An electrical sterilizer comprising a supporting casing having a substantial widened base portion and a central upstanding tubular column, a metallic liquid container of electrical conductivity having a tubular column extending through the column portion of said casing and an extended heating chamber at its lower portion located within the base portion of said casing, an electrical heating element within the heating chamber of said liquid container, and a detachable collar element mounted on the upper end of the column portion of said outer casing for supporting an article dependently within the inner column portion of the device for sterilization.

2. An electrical sterilizer comprising an outer supporting casing having a base portion of substantial width and a central upstanding tubular column, a liquid container comprising a lower heating chamber located within the base portion of said outer casing and having a metallic bottom closure of electrical conductivity, said liquid container having a tubular column portion extending through the tubular column of the outer casing, a detachable article supporting collar element mounted on the outer end of the column portion of the outer casing, a pair of electrodes spaced apart and insulated from each other in their mounting within the heating chamber of said liquid container, said electrodes being separately connected in an electric circuit, the one directly to a circuit wire and the other through the metallic bottom of the container to a circuit wire, the electric circuit being completed by the liquid in the container in body sufficient to connect the two electrodes.

3. The herein described sterilizer, comprising an outer supporting casing having a cylindrical base portion of substantial diameter and a central upstanding tubular column and being open at its opposite ends, an inner liquid container having a tubular open ended upper portion flanged annularly at its upper end to overhang the adjacent end of the column portion of the outer casing and being supported throughout its extent within said column portion and insulated therefrom, said inner container having an enlarged

- cylindrical lower portion constituting a heating chamber and disposed within the base portion of said outer casing, the bottom of the heating chamber being composed of metal of electrical conductivity and detachable, electrical heating means within said heating chamber comprising a pair of vertically opposed disc-like electrodes in spaced relation and insulated from each other, said electrodes being located centrally of the heating chamber in the lower portion thereof, one directly in electrical contact with the bottom of the heating chamber and the other having an insulated terminal extended outside the chamber bottom, and separate electrical circuit wires connected to said upper and lower electrodes through said insulated terminal and metallic chamber bottom, respectively.
4. In an electrical sterilizer, an outer supporting casing, an inner liquid container made of electrically conducting material, supported within said casing and insulated therefrom, the outer casing having a base portion of substantial width and the inner container having a lower heating chamber portion within the base of the container, said outer casing having a central upstanding tubular column and the inner container having a tubular upper extension supported within the column of the outer casing, and heating means within the heating chamber of said inner container, said heating means comprising a disc-like electrode supported in electrical contact with the bottom of the heating chamber, and a similar electrode supported on an axial stem of insulation
- material above said first mentioned electrode, said stem extending through the lower electrode to the outside of the heating chamber through the bottom thereof, a securing bolt of electrical conductivity engaging and supporting the upper electrode on said insulation stem and extending outside the heating chamber through an axial bore provided therefor in said stem, a circuit wire attached electrically to said bolt, and an opposite circuit wire attached electrically to the bottom of the heating chamber portion of said inner container.
5. In an electrical sterilizer of the character described, an outer supporting casing having an upstanding tubular column portion, a tubular container extending through the column portion of the casing, the upper ends of the casing column and the container tube being open and coinciding, the bottom of the container tube being provided with a detachable metallic closure head of electrical conductivity, spaced electrodes in the bottom portion of the container and insulated from each other, one of said electrodes being in electrical contact with the closure head of the container and the other electrode electrically insulated from said closure head and having a combined securing bolt and electrical terminal element extended through the closure head and insulated therefrom, said securing and terminal bolt being connected to one of the circuit wires and the closure head connected to another of the circuit wires to a source of electrical energy.
